UNITED STATES PATENT OFFICE

164,007

DECORATED SHIRT OR THE LIKE

Florida Edwards Lewis, Hollywood, Calif.

Application September 9, 1950, Serial No. 12,129

Term of patent 7 years

(Cl. D3—25)

To all whom it may concern:

Be it known that I, Florida Edwards Lewis, a citizen of the United States, residing in Hollywood, in the county of Los Angeles and State of California, have invented a new, original, and ornamental Design for a Decorated Shirt or the like, of which the following is a specification, reference being had to the accompanying drawing, forming part thereof:

Fig. 1 is a front view of a decorated shirt or the like, showing my new design.

Fig. 2 is a back view thereof.

The repeat motifs, shown in dotted lines, are substantially similar to the motifs shown in full lines. The dominant feature of the design is shown in full lines.

I claim:

The ornamental design for a decorated shirt or the like, substantially as shown and described.

FLORIDA EDWARDS LEWIS.
